UNITED STATES PATENT OFFICE

MURRAY J. RYMLAND, OF BALTIMORE, MARYLAND

SPRING CUSHION UNIT

Application filed December 7, 1931. Serial No. 579,616.

The invention relates to spring cushion constructions for use in upholstered furniture, mattresses, automobile seats and other desirable and related installations.

More specifically the improved spring construction is of a character where each coil spring is housed within its individual compartment or chamber within the fabric or other walls of the spring cushion unit and the object of the invention primarily is to obtain greater life and durability of the structure as a whole, as well as obtaining material economies in manufacture.

The spring cushion construction and assembly contemplated by the invention is of a simple and yet efficient nature and is designated to obtain more convenience and facility in the insertion of the spring units, and the invention further provides insurance against wear and deterioration of the compartment walls at the localities where such wear is most likely to occur.

A still further object is to afford more play and movement to each individual spring, at the same time insuring against its displacement from its individual compartment and contact with any adjacent spring of the cushion unit.

A still further object is to provide a spring cushion unit in which the building up of the various partitions forming the spring compartments is facilitated in that the exact location of certain of these partition walls may be readily determined by the stitching which secures other walls of said compartments to the unit.

A further object is to provide material economies in the utilization of strips of fabric material which would otherwise be discarded as waste in the manufacture of spring cushion units.

Numerous other objects and advantages of the invention will be apparent as it is better understood from the following description, which, taken in connection with the accompanying drawing discloses a preferred embodiment thereof.

In said drawing:

Fig. 1 is a perspective view of the spring cushion unit constituting a preferred em-

bodiment of my invention, a corner of said unit being cut away to illustrate the interior construction.

Fig. 2 is a vertical sectional view on line 2-2 of Fig. 3.

Fig. 3 is a plan view of the spring unit, a portion of the cover fabric being cut away to show the interior construction.

Fig. 4 is a perspective view of one of the fabric strips constituting an important part of my invention.

Fig. 5 is a perspective view of one of the longitudinal fabric strips detached.

Fig. 6 is a similar view of one of the vertically disposed crosswise strips, a plurality of which are adapted to be secured to the strip member shown in Fig. 5.

Referring to the drawing, a spring cushion unit of substantially square construction has been illustrated but it will be understood that the size and configuration of the unit may be varied without departing from the nature and scope of the invention. As illustrated the spring unit comprises a single piece of cloth or other fabric 1 which may be folded and stitched to enclose any desired number of spring units. Said fabric 1 is folded as at 2 to form an upper cover wall 3 and a lower or bottom wall 4, said walls having integrally downturned and upturned side wall portions 3a and 4a respectively, the extremities of said side walls being lapped together and suitably stitched or otherwise secured together as indicated at 5. When the assembly is complete the said cover and bottom portions are bent downwardly and upwardly at their ends as indicated at 3b and 4b respectively to form end walls the extremities of which are suitably stitched or otherwise secured together as shown at 6a.

I have provided a plurality of longitudinal partition strips 6 which may be formed of strips of fabric of relatively narrow width and which would otherwise be discarded as waste material in the manufacture of spring unit constructions as heretofore produced. Each strip 6 is or may be of a length commensurate with one dimension of the spring unit to be constructed and is provided at spaced intervals along its extent

with a plurality of angularly extending or vertically disposed cross-wise strip members 7. The members 7 correspond to and serve to form opposite walls of aligned spring compartments in the completed cushion unit and each cross-wise strip 7 is positioned on the strip member 6 so as to be in line with the center of each spring compartment. Said members 7 are suitably stitched or otherwise secured to the member 6 as shown at 8 to form a double thickness of fabric at this point (Fig. 4).

After the sheet of fabric 1 is doubled on itself to form the upper and lower walls of the cushion unit the strip members 6 with the strips 7 secured thereto, are positioned between said upper and lower walls and stitched in position to said walls by means of the flanged upper and lower extremities 9, 9 α of the strips 7. The said strip members 6 are positioned in predetermined spaced relation according to the size of the spring units to be inserted as best seen in Fig. 3. After the required number of strips 6 have been secured in position as described to the upper and lower walls of the fabric, a plurality of angularly disposed intermediate strips 10, each having upper and lower flanged extremities 11 and 11 α , are stitched or otherwise secured in position to the upper and lower walls of the fabric to complete the individual spring compartments. The described angularly disposed strip members 10 may also be formed of material which would otherwise be discarded and may be of substantially the same size as the strips 7.

From the foregoing it will be apparent that the arrangement of the longitudinal and intermediate strips 6 and 10 as described provides a plurality of adjacent spring compartments between the confining walls of the fabric 1, as best seen in Fig. 3. One side of the unit, comprising upper and lower walls 3b, 4b may then be drawn together and stitched at 6 α as described, and as seen in Figs. 1 and 3. In the same manner the end wall consisting of the fabric parts 3 α and 4 α may be similarly drawn together and stitched to complete three sides of the cushion unit. The individual coil springs, shown at 12, are next inserted in position in their respective individual compartments through the uncompleted side wall of the cushion, for example that shown at the right hand of Fig. 3. For this purpose a suitable spring inserting tool of usual or preferred construction is employed, each horizontal row of springs (Fig. 3) being positioned on said tool for insertion into the unit. The springs are compressed in the usual manner in spaced relation on the tool, thereby permitting the same to clear the spaced partition wall sections formed by the intermediate fabric strips 10. The tool is then turned at right angles and the springs are released to

position each spring in its individual compartment formed by the described strips 6, 7 and 10.

From the foregoing it will be apparent that the continuous longitudinal strip 6 serves as a guide for the insertion of the usual tool containing the springs in positioning each row of spring units. The latter may be of the desired resiliency to provide the proper degree of compression to the completed unit when the springs are released. After all of the springs have been inserted in position the open side wall of the unit is drawn together and stitched along the line 5 to complete the assembly.

The arrangement of each strip 6 with its spaced cross-wise strip members 7 provides a double thickness of material on opposite walls of each spring compartment to reinforce said walls and resist the wearing tendency of the spring units during the life of the article.

It will be further apparent that by my improved manner of constructing the cushion unit, the space lines of stitching 13 (Fig. 3) securing cross-wise strips 7 to the upper and lower walls 3 and 4 serve as guides to determine the proper location and position of the intermediate strips 7 which are later sewed in position. Since the cross-wise strips 7 form with the longitudinal strip 6 opposite walls of each compartment, the proper location of the intermediate strips 10, disposed at right angles to the stitching of strips 7 and between said rows, may be readily determined. This promotes and expedites the construction of the cushion units by the workman or operator.

What is claimed is:

1. In a spring cushion unit, the combination of a housing of fabric, a plurality of spring members arranged in longitudinal and transverse rows therein, a plurality of longitudinal fabric strips spaced apart and disposed in parallel relation within said housing to define the location of said rows of springs, each of said longitudinal strips having attached thereto vertical crosswise strips having their ends secured to the upper and lower walls of said housing, and vertical intermediate strips arranged between said longitudinal strips and between the springs secured to the upper and lower walls of said housing, all of said strips dividing the interior of the housing into separate compartments one for each spring and resisting the expansion of said springs and holding them in place and from horizontal movement relative to each other.

2. In a spring cushion unit, the combination of a housing of fabric, a plurality of spring members arranged in longitudinal and transverse rows therein, a plurality of longitudinal fabric strips spaced apart and disposed in parallel relation within said

housing to define the location of rows of said springs, each of said longitudinal strips having attached thereto vertical crosswise strips to form a double thickness of fabric on two sides of each compartment, the ends of said crosswise strips being secured to the upper and lower walls of said housing, and vertical intermediate strips arranged between said longitudinal strips and between the springs of each row, the ends of said intermediate strips being secured to the upper and lower walls of said housing, all of said strips dividing the interior of the housing into separate compartments one for each spring, whereby the said double thickness of fabric resists the wearing tendency of said springs during expansion and contraction.

3. In a spring cushion unit, the combination of a housing of fabric having compartments for springs, a plurality of springs arranged in longitudinal and transverse rows and individually disposed in said compartments, said compartments being formed by placing within the housing a series of vertical strips one between the springs of each pair of springs in adjacent longitudinal rows said strips having their opposite ends secured to the upper and lower walls of said housing, and means connecting with each other the middle portions of said vertical strips, thereby forming a double wearing thickness between corresponding springs of adjacent longitudinal rows to resist the wearing tendency of the springs.

35 In testimony whereof, I affix my signature.

MURRAY J. RYMLAND.
